ABSTRACT: An apparatus is provided for mechanically removing oils and floating non-adherent emulsions from waste water subsequent to the latter attaining a substantially quiescent state and the oils and emulsions thereof having been treated with a preferential absorbent material to form non-floating masses. The apparatus includes an elongated horizontally disposed planar member mounted within a reservoir and slightly beneath the level of the substantially quiescent waste water accumulated within the reservoir. The planar member is disposed between a water inlet and a water outlet for the reservoir and is adapted to have deposited thereon the non-floating masses. A conveyor means having a plurality of elongated flights is also provided wherein the flights thereof engage and move across the planar member carrying therewith the deposited masses and discharging same at a predetermined discharge station.

PRODUCT HANDLING APPARATUS

BACKGROUND OF THE INVENTION

Various apparatus have heretofore been provided which, however, because of certain design characteristics are ineffective in removing both oils and floating nonadherent emulsions from waste water, have low capacities, and/or are costly to install and maintain.

SUMMARY OF THE INVENTION

Thus, it is an object of this invention to provide an apparatus of the type described which is not beset with the shortcomings of the prior apparatus.

It is a further object of this invention to provide an apparatus of the type described which may be readily installed in existing reservoirs, sump tanks, or the like.

It is a further object of this invention to provide an apparatus which is capable of handling oils and floating nonadherent emulsions as well as various solids which are entrained in the waste water.

Further and additional objects will appear from the description, accompanying drawings, and appended claims.

In accordance with one embodiment of the invention, an apparatus of the type described is provided which includes a reservoir having a water inlet and a water outlet. The reservoir is provided with means for maintaining the waste water at a predetermined first level while at a substantially quiescent state within the reservoir. Disposed therein and at a predetermined second level, which is in close proximity to but beneath said first level, is an elongated horizontally disposed planar member. The planar member is positioned between the water inlet and outlet and has mounted along the elongated edge thereof closest to the water outlet, an upright partition which extends from the second level above the level of the accumulated waste water. The upright partition and planar member cooperate with one another to form a collection area wherein the oils and floating emulsions are corralled and subsequently treated with an absorbent material causing nonfloating masses to form which become deposited on the planar member. A vertical ramp is provided which is disposed adjacent one side wall of the reservoir and extends upwardly to an elevated discharge station. The lower end of the ramp is connected to an adjacent end of the planar member by a curved plate section. A power-actuated conveyor means is also provided which includes a plurality of elongated flights which are adapted to successively engage the deposited masses and move same across the planar member, over the curved plate section, and then up the ramp to the discharge station.

DESCRIPTION

For a more complete understanding of the invention reference should be made to the drawings wherein:

FIG. 1 is a fragmentary top plan view of one form of the improved apparatus.

FIG. 2 is a fragmentary sectional view taken along line 2-2 of FIG. 1.

FIG. 3 is a fragmentary sectional view taken along line 3-3 of FIG. 1.

Referring now to the drawings, one form of the improved apparatus 10 is shown which includes a reservoir or tank 11 formed in the illustrated embodiment of reinforced concrete and having a substantial portion thereof recessed with respect to the ground surface. If desired, however, the entire reservoir may be disposed above ground. The reservoir 11 has an end wall 12 provided with a waste water inlet 13 and the opposite end wall 14 provided with a water outlet 15. The interior surface of end wall 12 is inclined downwardly at a substantial angle as seen in FIG. 2. Intermediate the end walls 12 and 14 may be provided an upright auxiliary wall 16. The side of the wall 16 adjacent the inlet 13 is also partially inclined downwardly but at a lesser angle than end wall 12. End walls 12 and 14 and auxiliary wall 16 are interconnected at their corresponding opposite ends by side walls 17 and 18.

Disposed within reservoir 11 is a first frame assembly 20 which includes an elongated horizontally disposed planar member 21, a vertically extending ramp 22, and a curved plate section 23 which interconnects the lower end of ramp 22 with the adjacent end of the planar member 21. The planar member 21 is adjustably supported in a substantially horizontal plane by a pair of elongated, substantially parallel support members 24, at least one end of each being preferably secured to side wall 17 of the reservoir 11. If desired, however, the frame assembly 20 may be supported within the reservoir by other means than that shown.

Cooperating with and mounted on frame 20 is a conveyor assembly 25 which includes a pair of endless chains 26 interconnected to one another by a plurality of elongated, spaced, parallel, transversely extending flights 27. Each flight has the elongated axis thereof disposed normal to the direction of movement of the chains and each flight has a length which corresponds substantially to the width of the planar member 21.

Mounted on frame 20 and adjacent the elongated side of the planar member 21 disposed closest to outlet 15 is an upright partition or baffle 28. The partition 28, planar member 21, and walls 17 and 18 of the reservoir cooperate with one another to form a collection area A in which the oils and emulsions of the inflowing waste water are corralled. It will be noted that planar member 21 is spaced inwardly from the inlet 13 so that any heavy solids entrained in the inflowing waste water will gravitate along the inclined wall surface to the bottom of the reservoir. The planar member is normally immersed approximately 1 1/4 inches beneath the level of the accumulated waste water when the water inflow rate is approximately 1000 gpm. Where the inflow rate is increased the immersion depth of planar member is normally increased (e.g. inflow rate 2000 gpm, immersion depth approx 3"). Suitable means 24' may be provided to permit vertical adjustment of the support members 24.

Once the oils and floating nonadherent emulsions of the inflowing waste water have been corralled in area A, a preferential absorbent material (e.g. sawdust) is spread over the surface of the waste water disposed within area A. The corralled oils and emulsions coat with the absorbent material to form nonfloating masses which deposit on the adjacent planar member surface. To prevent entrapment of any oils or emulsions beneath the planar member 21, the support member 24 disposed closest to the inlet 13 is provided with weep holes through which the oils and emulsions may pass.

The partition 28, if desired, may be provided with a depending portion 28a which terminates a predetermined distance above the bottom of the reservoir. Partition portion 28a serves to prevent or minimize the migration of the oils and emulsions downstream of the frame 20.

The flights 27 of conveyor assembly 25 are adapted to successively engage the nonfloating masses deposited on planar member 21 and move same thereacross, over the curved surface of plate section 23 and then up vertical ramp 22 to an elevated discharge station S, see FIG. 3. The pair of chains 26 and flights 27 carried thereby are directed through the aforescribed segments of travel by a plurality of sprockets 30a-c. Sprocket 30a is preferably driven by a suitable motor 31 which is mounted on a bracket 32 extending from frame 20.

After each flight has deposited its waste masses at the discharge station S, the flight moves about the sprocket periphery and then downwardly in a catenary path to idler sprocket 30b. The operation of motor 31 may be controlled by a suitable timing mechanism, not shown, so as to coincide with the waste water inflow.

Resting upon the bottom of reservoir 11 and in vertical alignment with frame 20 is a second frame 120. Frames 20 and 120 are of like construction and therefore corresponding parts thereof will be numbered the same except in the case of frame 120 the numbers will be in the one hundred series. In frame 120 the vertical ramp 122 thereof is disposed adjacent the opposite reservoir wall 18, as seen more clearly in FIG. 3. It will

be noted in the form of the improved apparatus shown in FIG. 3 that the length of frame planar member 21 is foreshortened an amount sufficient to permit the vertical ramp 122 of frame 120 to pass upwardly between the end of planar member 21 and the reservoir wall 18.

Cooperating with frame 120 is a conveyor assembly 125 which is of substantially the same construction as conveyor assembly 25, except in assembly 125 as each flight 127, subsequent to passing over drive sprocket 130a, is guided vertically downwardly in a plane parallel to the reservoir wall 18, and then horizontally to idler sprocket 130b. The change in direction of the depending flight 127 to the horizontal may be accomplished by an additional spring loaded idler sprocket 130d.

Upon the flights 127 leaving sprocket 130b, each engages the waste solids which have gravitated to and accumulated on planar member 121. As each flight moves from sprocket 130b to sprocket 130c, the engaged masses move therewith and then the loaded flight moves over the curved surface of plate section 123 and up ramp 122 to a second elevated discharge station Y.

The length of planar member 121 substantially spans the distance between reservoir walls 17 and 18 and the width thereof substantially coincides with the width of the reservoir bottom 19 which is partially delimited by the inclined inner surfaces of wall 12 and auxiliary wall 16. The frame 120 adjacent planar member 121 is open permitting the waste solids to readily gravitate to the planar member, see FIG. 2.

When the inflow waste water does not have entrained therein solids (e.g. metal chips or filings), the second frame 120 and associated conveyor assembly 125 may be omitted.

The level of the waste water in the reservoir 11 may be controlled by a suitable pump P located within the area between auxiliary wall 16 and wall 14. The top of wall 16, it will be noted, is beneath the level of the accumulated waste water and prevents further migration of the solids past the wall 16. The discharge from the pump is directed out through outlet 15. Suitable control means, not shown, may be provided for pump P to effect automatic operation thereof and thus maintain the accumulated waste level at a predetermined level within the reservoir. Various other means besides pump P may be employed, if desired, to maintain the accumulated waste water at a predetermined level.

Thus, it will be seen that a simple and effective apparatus has been provided for the removal of oils and floating nonadherent emulsions and the like from waste water. The apparatus is capable of being readily installed in various types of reservoirs, sump tanks, etc. and is adapted to have a capacity capable of handling volumes of water varying over a wide range and having entrained therein a variety of floatable and nonfloatable waste products.

I claim:

1. An apparatus for removing oils and floating nonadherent emulsions from waste water subsequent to the latter assuming a substantially quiescent state and a predetermined portion of the surface of the quiescent water being treated with a

preferential absorbent material whereby the oils and floating emulsions coat with said material to form nonfloating masses, said apparatus comprising a reservoir in which the waste water is accumulated and assumes the substantially quiescent state;

5 5 a water inlet at one end of the reservoir; means for retaining the accumulated water at a predetermined first level; an elongated horizontally extending planar member disposed at a predetermined second level in close proximity to but beneath said first level and on which the nonfloating masses are collected, said planar member spanning substantially the distance between the sides of the reservoir interconnecting the ends thereof and being positioned intermediate said water inlet and outlet; a partition disposed adjacent the elongated side of said planar member adjacent the water outlet and projecting up-10 wardly from said second level and substantially above said first level, said partition and planar member cooperating to form a collection area for the oils and floating emulsions of the inflow waste water and prior to the oils and emulsions being treated with the absorbent material; a vertically extending ramp disposed adjacent one side of the reservoir connecting the ends thereof and extending upwardly therefrom to an elevated discharge station, the lower edge of said vertical ramp being connected to the adjacent edge of the planar member by a curved section; and power-actuated conveyor means having a 15 plurality of flights mounted for successively engaging the collected nonfloating masses and moving same across said planar member, around said curved section, and up said vertical ramp to said discharge station.

2. The apparatus of claim 1 wherein said planar member is supported by and is vertically adjustable relative to said reservoir sides.

3. The apparatus of claim 1 wherein said partition includes a section depending from said second level and terminating a predetermined distance from the bottom of the reservoir whereby only substantially oil-free water and emulsion-free water is caused to flow therebeneath.

4. The apparatus of claim 1 wherein each flight has a length substantially coextensive with the width of said planar member.

5. The apparatus of claim 1 including an elongated horizontally extending second planar member disposed beneath said first mentioned planar member and on which waste solids are collected; a second vertically extending ramp disposed adjacent the second side of said reservoir and extending upwardly therefrom to an elevated second discharge station, the lower edge of said second vertical ramp being connected to an adjacent edge of the second planar member by a second curved section; and a second power-actuated conveyor means having a plurality of flights mounted for successively engaging the collected waste solids and moving same across said second planar member, around said second curved section, and up said second ramp to said second discharge station.

6. The apparatus of claim 5 wherein said second planar member is disposed adjacent the bottom of said reservoir and said first and second planar members are in registered relation with respect to one another.
